UNITED STATES PATENT OFFICE.

ANTON H. RINTELMAN, OF CHICAGO, ILLINOIS.

SOUND-REPRODUCING MACHINES.

1,252,843.

Specification of Letters Patent.

Patented Jan. 8, 1918.

Application filed March 14, 1917. Serial No. 154,856.

To all whom it may concern:

Be it known that I, ANTON H. RINTELMAN, a citizen of the United States, and a resident of Chicago, in the county of Cook and State of Illinois, have invented certain new and useful Improvements in Sound-Reproducing Machines, of which the following is a full, clear, and exact specification.

My invention is concerned with the styli 10 and their supporting mechanism used in sound-reproducing machines, and is designed to produce such styli and so support them as to produce the very best possible reproduction of the tones recorded and to enable me to vary the loudness of said tones at will.

To this end, I have devised a novel needle or stylus, preferably with a plurality of points to adapt it for the different types of 20 this record, such as the zigzag Columbia and Victor records, and the hill-and-dale Edison and Pathé records, together with a holder therefor, which enables me not only easily to position the needle perfectly relative to the groove in the disk, but also to regulate within a very wide degree the loudness of the tone produced by the single needle, without impairing the quality thereof.

To illustrate my invention, I annex here- 30 to a sheet of drawings, in which the same reference-characters are used to designate identical parts in all the figures, of which,—

Figure 1 is a side elevation of a sound- 35 box and a part of a tone arm having my invention applied thereto;

Fig. 2 is a central longitudinal section, on an enlarged scale, through the needle-holder in a plane parallel to the face of the dia- 40 phragm;

Fig. 3 is a similar view, but with the needle adjusted for a lighter tone;

Fig. 4 is a cross section, on a still larger scale, on the line 4—4 of Fig. 2;

Fig. 5 is an end view of the needle de- 45 tached, on the same scale as it appears in Fig. 4; and

Figs. 6, 7 and 8 are side elevations of the needle as seen from three different sides.

In carrying out my invention, I employ 50 any customary sound-box 10 provided with the customary needle-bar 11, suitably journaled, as in the bearings 12 carried by the sound-box, and having the customary needle- 55 socket 13 with the customary set-screw 14.

Of course these can be varied for the different make of machine which is employed.

The needle 15 is made of a bar of some crystalline homogeneous mineral which has the proper hardness for the purpose. The 60 bar is preferably of substantially uniform dimensions throughout its length, and is likewise preferably in the form of a regular polygon in cross section, said cross section preferably being an equilateral triangle, and it is preferably small enough so that it will fit in the socket of an ordinary needle-holder in the same manner as the well-known triangular fiber needles, in case the user desires to procure the greatest 65 possible loudness of tone from the use of the needle, in which case it will be placed directly in the socket 18 and secured in the same manner as the ordinary fiber needle. For such use, it is preferably provided on 70 one end with the point 16 formed by beveling off that end. On the other end, I preferably form two points 17 and 17', which may be just alike, and a third point or ball 18, which is preferably adapted for a Pathé 75 record, as will be hereinafter described. To produce these points, I grind out the concavities 19 in the sides of the needle at that end, and as the concavities increase in depth from the point where they begin on the sides 80 of the needle to the end thereof, their grinding produces the two points 17 and 17', which have a much finer angle than the sixty degrees which would result if the end were cut or ground off flat without these 85 concavities. For the Pathéphone point or ball 18, I round off the point produced by the adjacent concavities 19, and below the point, I grind out a recess 20, which enables the needle to stand at the proper angle on 90 a Pathé record, and still make proper contact at all points thereon.

To control more perfectly the setting of the needle, as well as the loudness and quality of the tone, I employ in connection therewith the auxiliary holder 21, which preferably takes the form of a cylindrical cup having the stem 22 extending longitudinally from the center of the closed end and adapted to enter the socket of the needle- 100 holder and be secured therein by the set-screw 14 in the same manner that a needle is secured in said socket. The upper half of the cylindrical aperture 23 in the socket is filled by a block of soft rubber 24 which is 105

properly shaped to fill substantially one-half of the socket, and which for the triangular needle shown is preferably substantially semi-circular in cross section. The 5 flat surface furnishes a bearing for one side of the needle, and I preferably employ a set-screw 25 for the auxiliary holder, which is threaded through a suitable aperture in the side, and the end of which passes 10 through a suitable aperture 26 in the rubber so that the end of the screw can engage one of the sides of the needle or stylus 15. A function of this rubber top is to make it 15 resilient in case of an accident, such as dropping the tone arm on the record, thereby saving the needle, as well as the record, from injury.

The lower half of the socket is filled by a 20 pad 27, which is preferably of fiber cloth made of raw hemp or flax and interwoven with wool. This pad is of the proper shape on the side adjacent to the rubber block 24 so as to form a socket of the proper shape to receive the body of the needle without 25 any further compression of the pad. To keep the aperture or socket for the needle in proper shape to correspond with its cross section whether the needle is pushed partly in or all the way in, I line preferably all 30 three sides of the socket with strips 28 of bamboo fiber. These strips are glued securely to the block 24 and to the pad 27.

I have already pointed out that to obtain 35 the loudest tone, the needle 15 will be placed directly in the regular socket 13, but where softer tones are to be employed, the auxiliary holder 21 is employed, and the needle 15 is thrust into its socket as far as it will go, so that the end which is not in use will 40 engage the metallic bottom of the socket. The set-screw 25 is then screwed up tightly so that its end engages directly with the fiber strip 28 pressing it against the needle, and this gives the greatest possible vibration 45 of the diaphragm, and consequently the loudest possible tone when the auxiliary socket is used. If the tone is to be made slightly softer, the set-screw 25 is turned back so that its end does not engage the fiber 50 28. If a still softer tone is desired, the needle 15 is pulled out so that its end that is not in use is out of engagement with the bottom of the socket, as shown in Fig. 3, and the set-screw 25 may be tightened to 55 any desired extent, thus furnishing a further modification of the tone. It will of course be understood that the farther the needle is drawn out, the softer the tone.

The point 16 is used in the manner shown 60 on Victor and Columbia records, and the points 17 and 17' may be similarly used by reversing the needle and placing the side opposite to the point that is to be used in

register with the set-screw 25. This set-screw is set at an angle parallel to the axis 65 of the fulcrum of the needle-arm 11, *i. e.*, at right angles to the set-screw 14, and this makes a ready means of setting the needle at the proper angle relative to the groove. Where the needle is to be used for an Edison 70 record, it will of course be used with a sound-box set at the proper angle thereto, and the points 16 or 17 or 17' may be used. When it is to be used with a Pathé record, the sound-box will of course be set in the 75 same manner as for an Edison record, but the point or ball 18 will be employed.

While I have herein disclosed my novel stylus, I do not herein claim the same, as it is covered by my application No. 324, filed 30 January 4, 1915, and while I have shown my novel tone modifying and regulating holder as employed with this specific stylus, for which it was especially devised, it will be understood that it can be used in the same 35 manner and for the same purpose with other different styli, such as are commonly in use.

While I have shown and described my invention as embodied in the form which I 90 at present consider best adapted to carry out its purposes, it will be understood that it is capable of modifications, and that I do not desire to be limited in the interpretation of the following claims except as may be 95 necessitated by the state of the prior art. I am aware of the structure shown in the patent to Haile, No. 963,546, dated July 5, 1910, and do not claim the same as my invention.

What I do claim as new, and desire to 100 secure by Letters Patent of the United States, is:

1. A needle-holder of inelastic and unyielding material for talking-machines having a cylindrical pocket in which is placed 105 a cushioning block of soft rubber in the upper half of the pocket divided along its length, and a soft fibrous pad in the lower half, the meeting faces of the block and pad being shaped so as to receive the body of 110 the needle without further compressing them.

2. A needle-holder of inelastic and unyielding material for talking-machines having a cylindrical pocket in which is placed 115 solid cushioning material engaging the sides of the pocket and having the needle-holding socket along the center of the axis, and a hard lining corresponding to the shape of the needle secured in said socket. 120

In witness whereof, I have hereunto set my hand and affixed my seal, this ninth day of March, A. D. 1917.

ANTON H. RINTELMAN. [L. S.]

Witness:

JOHN HOWARD McELROY.
